UNITED STATES PATENT OFFICE.

CHARLES A. MAY, OF TRENTON, NEW JERSEY, ASSIGNOR TO THE MADDOCK POTTERY COMPANY, OF SAME PLACE.

DESIGN FOR A EWER.

SPECIFICATION forming part of Design No. 25,790, dated July 21, 1896.

Application filed June 6, 1896. Serial No. 594,630. Term of patent 7 years.

To all whom it may concern:

Be it known that I, CHARLES A. MAY, a citizen of the United States, residing at Trenton, in the county of Mercer and State of New Jersey, have invented and produced a new and original Design for Ewers, of which the following is a specification.

In the accompanying drawing the ewer is represented in perspective.

The leading feature of the design consists in the vertical extensions *a a* at the upper end and on opposite sides of the ewer and the elliptical openings *b b*.

The mouth of the ewer projects a considerable distance above the extensions *a a*, and an embossed figure curved upward on the

mouth and downward and inward toward the opening *b* is provided on each side of the ewer.

The body of the ewer is provided with curved depressions and projections extending from the neck of the ewer downward toward the base, and above the depressions and projections are scroll-like embossed figures.

What I claim is—

The design for a ewer substantially as herein set forth.

In testimony whereof I affix my signature in presence of two witnesses.

CHAS. A. MAY.

Witnesses:

A. H. LEDDEN,
J. W. HENNEY.
